UNITED STATES PATENT OFFICE.

JOHN EDWARD LEWIS OGDEN, OF LISCARD, ENGLAND.

PRESSURE-PUMP AND VACUUM-TRAP.

1,134,405.

Specification of Letters Patent.

Patented Apr. 6, 1915.

Application filed January 12, 1914. Serial No. 811,701.

To all whom it may concern:

Be it known that I, JOHN EDWARD LEWIS OGDEN, a subject of the King of Great Britain and Ireland, and resident of "Penshurst," Lincoln Drive, Liscard, in the county of Chester, England, engineer, have invented certain new and useful Improvements in Pressure-Pumps and Vacuum-Traps, of which the following is a specification.

10 This invention relates to pressure pumps and vacuum traps adapted for pumping fluids or discharging same from vessels in which the pressure is less than atmospheric.

15 Referring to the accompanying explanatory drawings: Figure 1 is a sectional elevation of a pressure pump and vacuum trap constructed in one convenient form in accordance with my invention. Figs. 2 and 3 illustrate respectively the adaptation of my 20 improved apparatus for discharging liquid from a vessel under a vacuum, and for pumping liquid from a low to a high level.

The same reference letters in the three views indicate the same or similar parts.

25 I make the apparatus casing *a* of any suitable form and provide an inlet *b* and an outlet *c* thereon. The float *d* which acts in the manner of a floating piston (and is hereinafter so termed) is adapted to be an easy 30 fit within the casing *a* and slides upon a sleeve like element *e* or a rod guided at its lower end by a pin *f* projecting into the casing from the bottom thereof and at its upper end by the guide portion of a valve *g* which 35 is attached to said spindle or rod *e*. The said valve *g* serves to control communication between the vacuum or vapor space of the system being drained and the casing *a*. Or, in the case when the apparatus is used 40 for pumping purposes only, the said valve controls communication with the atmosphere by the pipe *g'*, see Fig. 3. It has a cylindrical piston like portion thereon as shown adjacent to the guide wings and preferably 45 also a conical or miter portion. The valve is actuated partly by the floating piston *d* and partly by the difference of pressures at its two sides as hereinafter explained. Adjacent to said valve *g*, which will be herein- 50 after termed the equalizing valve, a second valve *h*, hereinafter termed a pressure valve, is provided to control the flow of steam or air under pressure to the float chamber *a*, the said valve being operated by a rod or 55 arm *i* coöperating with the valve *g* so that the two valves act in unison.

The operation of the apparatus when arranged as shown in Fig. 2 is as follows: Assuming that the casing *a* is empty, the floating piston *d*, which is of the closed type, will be at the bottom of the casing *a* and will engage a stop *j* upon its central guiding sleeve or rod *e* so as to open the equalizing valve *g* and simultaneously allow of the closing of the valve *h* by the withdrawal of its operating arm *i* from contact with the valve stem; the valve *h* is then closed by the steam or air under pressure. The casing is now exhausted and placed under a vacuum so that liquid can flow there- 60 to by gravity from the pipe or vessel *m* being drained. As the casing *a* fills, the floating piston *d* rises and eventually engages the underside of the equalizing valve *g* or a part attached thereto so as to cause the 65 piston portion of said valve to cut off communication between the casing and the vapor space of the pipe or vessel being drained. Simultaneously the arm *i* operating the valve *h*, engages the stem of that 70 valve and partially opens the latter. The casing *a* is then placed under pressure and this results in the conical portion of the equalizing valve *g* being forced upon its seat by the difference of pressures at its two 75 sides and also in the full opening of the valve *h*. The pressure then acts upon the upper surface of the floating piston *d* (the latter acting as a piston and when required as a non-conductor of heat between the gas- 80 eous fluid and water) and expels the water from the apparatus through the discharge valve *k*. It will be readily understood that as the floating piston is an easy fit within the casing *a*, there is only a small area for 85 the pressure agent, which may be steam, to contact with the water around the piston and thus economy of steam is insured. Further, when the floating piston is in its up- 90 permost position, there is a minimum of 100 clearance space so that the discharge takes place promptly upon the opening of the valve *h*. The floating piston *d* is a closed vessel containing air and acts as an insu- 95 lator for preventing condensation of the steam when the latter acts as the pressure agent, by the relatively cold water in the apparatus. I provide non return valves on the apparatus inlet and outlet, and also a 105 spring or like loaded valve upon the outlet 110 so that the apparatus may work under any desired pressure. A safety valve may be

fitted upon the casing to prevent an excessive pressure being applied thereto through the valve h for discharging purposes. The discharge may be performed by gravity instead of by steam pressure. In such case, I may arrange for the admission of air by the valve h . Or, the discharge may be effected by compressed air and the valve g serve to control communication with the atmosphere.

10 This adaptation of my invention is shown in Fig. 3. The apparatus serves to raise liquid from the tank m to the tank n . It will be seen that in accordance with my invention, the float d on its up-stroke only causes the piston portion of the equalizing valve g to cut off communication between the casing and vapor space of the vessel being drained, the remainder of the closing movement of such valve and also the final 15 opening movement of the pressure valve h being accomplished by the increase of pressure in the float chamber a . I thereby insure the full opening of the valve h and the full closing of the valve g at each upward 20 stroke of the float.

25 Having now described my invention what

I claim as new and desire to secure by Letters Patent is:—

1. A pressure pump and vacuum trap, comprising in combination, a casing having 30 inlet and outlet ports, a floating piston in said casing, a rod guiding said piston and operated by the latter, an equalizing valve on said rod, a pressure valve, and an arm engaging said equalizing valve and operating said pressure valve, as set forth.

2. A pressure pump and vacuum trap, comprising in combination, a casing having inlet and outlet ports, a floating piston with 40 in said casing, a rod guiding said piston and operated thereby, an equalizing valve upon said rod having piston and miter portions, a pressure valve, and an arm operating the latter valve and engaging the equalizing valve, as set forth.

45 In testimony whereof I have signed my name to this specification in the presence of two subscribing witnesses.

JOHN EDWARD LEWIS OGDEN.
